UNITED STATES PATENT OFFICE

144,752

DESIGN FOR A DISPENSING UNIT FOR FILLING STATIONS

Wilbur H. Adams, Erie, Pa., assignor to Erie Meter
Systems, Inc., Erie, Pa., a corporation of Penn-
sylvania

Application June 1, 1945, Serial No. 119,845

Term of patent 14 years

(Cl. D52—2)

To all whom it may concern:

Be it known that I, Wilbur H. Adams, a citizen
of the United States, residing at Erie, in the
county of Erie and State of Pennsylvania, have
invented a new, original, and ornamental De-
sign for a Dispensing Unit for Filling Stations,
of which the following is a specification, refer-
ence being had to the accompanying drawing,
forming a part thereof.

The figure is a perspective view of a dispensing
unit for filling stations showing my new design.

The unit is symmetrical.

I claim:

The ornamental design for a dispensing unit
for filling stations, substantially as shown and
described.

WILBUR H. ADAMS.
